PERPETUAL CALENDAR

Violette A. Whyatt, Los Angeles, Calif.

Application June 2, 1938, Serial No. 211,446

3 Claims. (Cl. 40—115)

This invention relates to an improved perpetual calendar adapted for desk use or the like, and capable of being readily actuated to at all times correctly indicate the month, date and day of the week.

It is an aim of this invention to provide a device which may be constructed in a variety of attractive designs, consisting of a limited number of parts coacting in a unique manner to indicate the day of the week and month, as well as the day of the week for any day of the month at a glance.

It is a further object of this invention to provide a device as aforementioned, which will be economical in construction, durable and capable of being quickly and easily operated for setting at the end of each month and each day.

Other objects and advantages of the invention will hereinafter become more fully apparent from the following description of the drawing which illustrates a preferred form of the invention, and wherein:

Figure 1 is a front elevational view of the device.

Figure 2 is a vertical central sectional view of the same with the stand shown partly in elevation,

Figure 3 is a fragmentary front elevational view showing the hub of the pilot wheel calibrated with the months of the year and the number of days in each month, and

Figure 4 is a fragmentary top plan view of the larger disk.

Referring more particularly to the drawing wherein like reference characters designate like or corresponding parts, 10 designates a stand or support which may be of any construction desired depending upon the construction of the remaining parts of the invention. Stand 10 is provided with an enlarged base 11 adapted to rest on any suitable supporting surface, and has a threaded bolt 12 projecting through its upper part with its threaded end exposed to receive the disk 13, wheel 14, disk 15 and two nuts 16 which retain parts 13 14 and 15 in position.

Disk 13 is substantially the same diameter as the rim 17 of the wheel 14, and is provided with seven rows of numerals, designated 18 to indicate the different date of each particular day of the week of a month, for instance, as seen in Figure 1 Sunday would fall on the first, eighth, fifteenth, twenty-second and twenty-ninth of the month. The wheel 14 comprises the hub 19 and the seven spokes 20 which project outwardly therefrom through the rim 17 and which have the handles

21 at their free ends to complete the design of a pilot wheel. The seven spokes 20 are adapted to divide the seven rows of calibrations 18 on disk 13 so that each row will be visible through one of the openings in the wheel as seen in Figure 1. 5

Hub 19 is provided with a reduced outer portion 22 as best seen in Figure 3, which is marked with the 12 months of the year and with the number of days in each month beneath each particular month as seen at 23. Disk 15 is provided with a cut-out portion 24 shaped to expose one of the months and its number of days 23 as best seen in Figure 1.

Between the spokes 20, rim 17 is marked with the days of the week as indicated at 25, so that each of the days 25 is directly above one of the rows of numerals 18. Disk 13, wheel 14 and disk 15 are rotatably mounted on bolt 12 and normally move together when actuated by one of the handles 21, but may be moved independently of each other as desired and as will hereinafter be explained.

From the foregoing it will be seen, that disk 15 can be turned relatively to wheel 14 to expose any desired month through cut-out portion 24, after which wheel 14 may be turned relatively to disk 13 until the first day of the month or the numeral 1 on disk 13 corresponds or is beneath the day of the week designated 25 on which the first day of that month happens to fall. Wheel 14 is then turned with disk 13 until the numeral 1 and its day of the week is at the top. Assuming that the month is May and the first day of the month is Sunday, the wheel 14 will be positioned as seen in Figure 1 and on the following day wheel 14 will be turned by one or more of the handles 21 one seventh of a turn counterclockwise to bring the word Monday to the top with the numeral 2 on the disk 13, and this will be continued throughout the month. At the beginning of the next month disk 15 will be turned relatively to wheel 14 one twelfth of a complete turn to expose the month of June and the first day of the month will then be positioned above the numeral 1 and the operation repeated. In this way it will be

seen that an efficient and practical calendar has been provided which may be used perpetually, and from which it may be ascertained at a glance what particular day of the week any date of the current month will fall on. For instance, on any day of the month by merely glancing at the calendar it can be ascertained that the thirtieth of May will be on a Monday.

The wheel 14 could obviously be made in the form of a wagon wheel or any other of many de-

signs, without affecting the operation of the device, and various other modifications and changes may be made and are contemplated, and the right is expressly reserved to make such variations and changes as do not depart from the spirit and scope of the invention as hereinafter defined by the appended claims.

I claim as my invention:

1. In a device of the class described, a calibrated disk, a wheel-shaped member mounted in front of said disk and having a plurality of spokes dividing the calibrated portions of the disk into seven parts, the rim of said wheel being marked with the days of the week and the hub with the months of the year, a member mounted in front of said hub having a cut-out portion to expose one of the months marked thereon, and a shaft on which said parts are rotatably mounted to move as a unit or separately to perpetually indicate the month, date and day of the week.
2. A perpetual calendar comprising a stand, a threaded bolt projecting through the upper part of said stand, a disk mounted on the bolt, a wheel-shaped member mounted in front of said

disk, and a second disk mounted in front of the hub of the wheel-shaped member and having a cut-out portion to expose a portion of said hub, said first mentioned disk and wheel-shaped member being calibrated to indicate the day of the week, its month and date, said parts being rotatably mounted to turn in unison or individually as required.

3. A perpetual calendar comprising a pedestal, a shaft mounted in the upper end thereof and projecting outwardly therefrom, a disk mounted on said shaft, a wheel mounted on said shaft in front of said disk and having a plurality of spokes dividing said disk into a plurality of corresponding sections, said disk and wheel being substantially the same diameter, a second disk mounted on said shaft in front of the wheel and of substantially the same diameter as its hub, said second disk having a cut-out portion exposing a part of said hub, said disks and wheel being rotatably mounted on the shaft relatively to each other whereby the parts may be revolved selectively or as a unit.

VIOLETTE A. WHYATT.
